FIG. 1.

FIG. 2.

FIG. 4.

FIG. 3

Inventor
Arthur Gillett Taylor
By *Wm. M. Clark* Attorney

UNITED STATES PATENT OFFICE.

ARTHUR GILLETT TAYLOR, OF STREATHAM, LONDON, ENGLAND.

WRENCH.

1,196,900.

Specification of Letters Patent.

Patented Sept. 5, 1916.

Application filed March 2, 1916. Serial No. 81,612.

To all whom it may concern:

Be it known that I, ARTHUR GILLETT TAYLOR, subject of the King of Great Britain, residing at 67 Mitcham lane, Streatham, London, England, have invented new and useful Improvements in Wrenches, of which the following is a specification.

This invention has for its object an improved adjustable wrench, the jaws of which are capable of being adjusted and used in various positions with respect to the handle according to the position of the nut, bolt-head, or other article to be gripped.

A further object is to provide means whereby the improved wrench may be caused to grip or to slide around the article at the will of the user.

According to this invention, one jaw has a stem which is screw threaded and provided with flat sides upon which the movable jaw slides, the stem screwing into and through a nut fixed to a handle and the lower portion of the boss of the movable jaw being arranged as a clutch to slide but not rotate upon the nut end of the handle; the movable jaw is caused to approach the adjustably fixed jaw by suitable means such as the bifurcated end of a grip lever acting against the boss of the movable jaw. Both jaws are (or may be) also capable of rotary adjustment about the axis of the fixed jaw stem, and of being set or fixed in the altered position.

The invention is illustrated by the accompanying drawings in which—

Figure 1 is a side elevation and Fig. 2 is a front elevation of the improved wrench; Fig. 3 is a sectional elevation of a modification and Fig. 4 is a section of Fig. 3 on the line A—B.

In carrying the invention into effect the stem *a* of the adjustably fixed jaw *b* is screw threaded at *c* and provided with flat sides *d*, the threads to engage in a nut *e* formed in or on, or attached to, a suitable handle *f*, and the flat sides to prevent the boss *g* of the movable jaw *h* from rotating on the stem *a*. A coil spring *i* is mounted on the stem *a* between the two jaws. A form of dog clutch (such as indicated at *k* in Figs. 1 and 2) is fitted between the movable jaw *h* and the nut *e*, the upper circular part of the clutch *l* engaging with the circular boss of the movable jaw *h* and the other part with the nut end of the handle so as to be capable of sliding thereupon but not capable

of rotating thereon. In the example shown this is effected by a rectangular formation of the lower part of the clutch which slides upon a corresponding formation of the nut end of the handle as shown in Figs. 3 and 4. A grip lever *m*, pivoted at *n* to the handle, is formed with a bifurcated end *o* embracing the exterior of the nut end of the handle and impinging against the lower end of the clutch *k*, so that when the user grips the lever *m* and the handle *f*, the clutch *k* and movable jaw *h* are driven toward the fixed jaw *b* (as indicated by the dotted lines in Fig. 1) against the pressure of the spring *i* which serves to separate the jaws when pressure on the grip lever *m* is relaxed. Thus, the jaws may be caused to grip the object or slip around same as required.

Both jaws are prevented from rotating by the clutch *k*, but the fixed jaw *b* may be adjusted by forcing the movable jaw *h* out of engagement with the clutch, when the jaws *b* and *h* and stem *a* may be rotated to screw the stem more or less into or through the nut *e* and so reduce or increase the span. The boss of the movable jaw *g* is constructed to engage the clutch in six or eight (or more or less) positions in one complete rotation of the stem in the nut, so that the jaws may be set to a position suitable for the particular use to which they are to be applied. For example, the dotted lines in Fig. 2 represent the jaws in a position 90 degrees from that shown in full lines. The jaws may be readily removed and replaced by others of different dimensions.

The clutch *k* may be made integral with or fixed to the boss of the movable jaw *h*, in which case the part *l* of the clutch is dispensed with, the lower part being slidable upon the nut end of the handle which may be rectangular as shown or of any other suitable polygonal section.

The handle *f* and grip lever *m* may be constructed and arranged in the manner shown in Figs. 1 and 2, or they may project in a more or less angular manner such as shown in Fig. 3, the position of the handle and lever which is adopted with respect to the body of the spanner or wrench being largely a matter of convenience or design or to suit particular circumstances.

I claim:

1. A wrench comprising a jaw, a screw threaded stem to which said jaw is fixed,

said stem being provided with flat sides, a movable jaw slidable upon the stem, a handle, a nut fixed to said handle and adapted to receive the stem, a clutch face on the lower part of the movable jaw slidable upon said stem, a clutch member slidable on said handle adapted to engage said jaw clutch face and to lock the movable jaw against accidental rotation, and hand operated means 10 to cause the movable jaw to slide upon the stem, as set forth.

2. A wrench comprising a jaw integral with a stem which is screw threaded and provided with flat sides, a movable jaw 15 slidable upon the stem, a coil spring on the stem between the two jaws, a handle, a nut fixed to said handle to receive the stem, a clutch slidably mounted on the nut end of the handle and provided with a clutch face 20 adapted to engage a corresponding clutch face on the boss of the movable jaw in any of several positions in one complete rotation of the jaw stem in the nut, and hand operated means to cause the movable jaw to 25 slide upon the stem, as set forth.

3. A wrench comprising a jaw integral with a stem which is screw threaded and provided with flat sides, a movable jaw slid- 30 able upon the stem, a coil spring on the stem between the two jaws, a handle, a nut

fixed to said handle to receive the stem, a clutch face on the lower part of the movable jaw, a clutch member slidable upon the nut end of the handle and adapted to engage said jaw clutch face to lock the movable jaw against accidental rotation, and a grip lever to cause the movable jaw to slide upon the stem, as set forth. 35

4. A wrench comprising a jaw integral with a stem which is screw threaded and provided with flat sides, a movable jaw 40 slidable upon the stem, a coil spring on the stem between the two jaws, a handle, a nut fixed to said handle to receive the stem, a clutch slidably mounted on the nut end of the handle and provided with a clutch face 45 adapted to engage a corresponding clutch face on the boss of the movable jaw in any of several positions in one complete rotation of the jaw stem in the nut, and a grip lever having a bifurcated end acting against the clutch to cause the movable jaw to slide 50 upon the stem, as set forth.

In testimony whereof I have signed my name to this specification in the presence of 55 a subscribing witness.

ARTHUR GILLETT TAYLOR.

Witness:

A. W. DOWNING.
